RICHARD A. LINK AND CONRAD F. HARDERS, OF DETROIT, MICHIGAN, ASSIGNEES TO
L. A. YOUNG COMPANY, OF DETROIT, MICHIGAN

SHAFT FOR GOLF CLUBS AND THE LIKE

Application filed May 1, 1929. Serial No. 359,500.

In the manufacture of wooden shafts for golf clubs it is the common practice to "bell" and shoulder the shaft so that the shaft merges or has the appearance of merging into the shank of the club. This is done for the purpose of appearance and also to secure the desired "bell" in the club.

One of the decided disadvantages or objections to steel-shaft clubs, particularly as applied to metal heads, is that the club does not have the appearance and it is very difficult if not impossible to secure the balance or "feel" which can be quite readily attained with a wooden shaft.

15 Our present invention is an adaptation of and in some respects an improvement upon the structure of our application for Letters Patent filed November 17, 1928, Serial No. 220,108.

20 It is the main object of this invention to provide a golf club having a steel shaft which closely simulates the wooden shaft clubs in appearance and has the desired balance.

Objects pertaining to details and economies 25 of our invention will definitely appear from the description to follow. The invention is defined in the claims.

The preferred embodiment of our invention is clearly illustrated in the accompanying drawing, in which:

30 Fig. 1 is a perspective view of a golf club having an iron head embodying the features of our invention, portions of the shaft being broken away.

35 Fig. 2 is an enlarged fragmentary view partially in longitudinal section.

Fig. 3 is a fragmentary longitudinal section illustrating one of the steps of one method of manufacturing our improved club.

40 In the accompanying drawing we have illustrated our improvements in one form in which we have embodied the same in practice, in which the iron club head 1 is provided with a downwardly tapered integral shank 2 having a socket 3 therein. The shaft 4 is of tubular steel, the walls of the shaft being of uniform thickness throughout. The grip 5 of leather or other suitable material is conveniently illustrated in the drawing.

50 The upper end of the shank or hosel is flat

thereby forming with the shaft a square-faced shoulder 6. On this shaft above the shank and in abutting relation thereto we affix an upwardly tapered sleeve 7 preferably of metal, aluminum being found very satisfactory for the purpose. The sleeve is shrunk on pressed or otherwise fixedly secured to the shaft so that it in effect becomes an integral part thereof in the assembled structure and provides a shoulder on the shaft abutting the end of the shank. This sleeve is preferably uniformly tapered to a feather edge as illustrated.

Between the grip and the end of the hosel we cover the shaft with a coating or sheath 8. This covering embraces the sleeve and covers the joint between the sleeve and the shaft and abuts the end of the shank. The diameter of the sleeve at its larger lower end is sufficiently less than that of the upper end of the shank so as to fill in the shoulder surrounding the base of the sleeve.

This outer covering is satisfactorily formed of a pyroxylin tubing. In Fig. 3 we illustrate the method of assembling, the covering being heated to permit its expansion, and then telescoped over the sleeve until its end abuts the shank, or the sleeve may be telescoped into the covering prior to the securing of the shaft in the head. The covering may be of other material than pyroxylin or it may be applied otherwise than as a separate sleeve or sheath. For convenience we have illustrated the same as a separately formed sheath which may, however, be applied by dipping, spraying or otherwise built up of pyroxylin or certain lacquers.

With this arrangement we are able to produce steel shaft clubs which very closely imitate the appearance of wooden shaft clubs, and also have the balance and "feel" so much desired.

We have not attempted to illustrate or describe certain further modifications and adaptations as we believe that this disclosure will enable those skilled in the art to embody or adapt our improvements as may be desired.

Having thus described our invention what we claim as new and desire to secure by Letters Patent is:

1. In a golf club, the combination of a metal head provided with a hosel having a socket therein the end of the hosel lying in a plane at right angles to its axis, a tubular steel shaft fitting and fixedly secured within said socket metal to metal, and an upwardly tapered metal sleeve immovably fixed upon said shaft metal to metal with its lower end in spaced relation to the lower end of said shaft, the lower end of said sleeve lying in a plane at right angles to its axis and being in supporting abutting engagement with the end of the hosel, the abutting surfaces of the hosel and sleeve being of substantial extent radially.
2. In a golf club, the combination with a metal head provided with a hosel having a socket therein, of a metal shaft fitting and fixedly secured within said socket in said hosel metal to metal, and an upwardly tapered metal sleeve immovably fixed upon said shaft metal to metal with its lower end in spaced relation to the lower end of the shaft and in supporting abutting engagement with the end of the hosel, the abutting surfaces of the hosel and sleeve being of substantial extent radially.
3. In a golf club, the combination with a metal head provided with a hosel having a socket therein, of a metal shaft fitting and fixedly secured within said socket in said hosel metal to metal and a sleeve of a metal lighter than the metal of the head tapered upwardly to a feather edge immovably fixed upon said shaft metal to metal with its lower end in spaced relation with the lower end of said shaft and in supporting abutting engagement with the end of the hosel, the abutting surfaces of the hosel and sleeve being of substantial extent radially.

In witness whereof we have hereunto set our hands.

CONRAD F. HARDERS.
RICHARD A. LINK.
